UNITED STATES PATENT OFFICE

114,439

DESIGN FOR A COMBINED SCALE EJECTOR AND SCREW DRIVER FOR DRAFTING MA- CHINES

David J. Christensen, Berkeley, Calif.

Application April 9, 1938, Serial No. 76,395

Term of patent 3½ years

To all whom it may concern:

Be it known that I, David J. Christensen, a citizen of the United States and resident of the city of Berkeley, in the county of Alameda and State of California, have invented a new, original, and ornamental Design for a Combined Scale Ejector and Screw Driver for Drafting Machines, of which the following is a specification, reference being had to the accompanying drawing, forming part thereof.

In the drawing:

Figure 1 is a perspective view of a combined

scale ejector and screw driver for drafting machines showing my new design.

Figure 2 is a plan view of the combined scale ejector and screw driver for drafting machines.

Figure 3 is an end elevational view of the combined scale ejector and screw driver for drafting machines.

I claim:

The ornamental design for a combined scale ejector and screw driver for drafting machines, substantially as shown.

DAVID J. CHRISTENSEN.
